Rodney G Richardson

UNITED STATES PATENT OFFICE.

RODNEY G. RICHARDSON, OF EDISON PARK, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed September 15, 1919, Serial No. 323,718. Renewed November 3, 1924.

To all whom it may concern:

Be it known that I, RODNEY G. RICHARDSON, a citizen of the United States of America, and a resident of Edison Park, county 5 of Cook, and State of Illinois, have invented certain new and useful Improvements in Automatic Telephone Systems, of which the following is a specification.

My invention relates in general to automatic telephone systems, but is more particularly concerned with means for giving measured service in such systems; and the chief object is to provide new principles and methods of operation, together with 10 suitable apparatus and circuits embodying these principles, thereby affording a more desirable and efficient measured service system than has hitherto been available. Other objects of the invention relate to the substation and exchange equipment and circuits therefor; and while such improvements are especially valuable in connection with a measured service system, it is conceived that 15 they may be of utility in other systems not so limited.

The embodiment of my invention shown herein is a paystation or coin collecting apparatus for use in automatic telephone systems. Apparatus of this general character 20 has been used for a long time and numerous types have been designed, all of which include a mechanism for collecting coins associated with an automatic substation, together with some arrangement whereby the 25 calling subscriber is compelled to deposit a coin for each successful call. As referred to these prior systems, a successful call means a call that has been answered. So far as known a call must be paid for every 30 time a connection is extended to another station and a response is secured, whether the desired number is obtained or not; and the calling subscriber has no redress in case he gets the wrong number through faulty 35 operation of the switching apparatus, because of wrong directory numbers, or by some other mishance not his fault. In manual systems where the operator collects the coin, a calling subscriber who gets the

wrong number can explain his difficulty 50 to the operator, and in a proper case can have his coin refunded; but hitherto automatic systems have not included this feature and consequently have not been as successful as they might have been. 55

My invention cures the objection above outlined and the preferred method of operation is as follows:

The substation is normally completely operative for outgoing calls as well as for incoming calls. This means that a connection can be established and conversation can be held without dropping a coin, or in other words, payment is deferred until the service is completely rendered. When the receiver is hung up at the calling station, however, it is disabled for further use so far as calling another subscriber is concerned, and a coin must be deposited to again render it operative. Ordinarily the subscriber will 60 do this at once, as there is no object in his delaying payment, although it will be seen that in an emergency, with no coin available, a connection can still be obtained and 65 can be paid for later on. Suppose now that 70 on account of some defect or other the calling subscriber gets the wrong number. He will of course hang up the receiver to release the connection, but will be unable to 75 call the number over again because of the disabled condition of his call sender. Not wanting to drop a coin for a call that was in reality unsuccessful, and through no fault 80 of his own, the subscriber now presses a 85 button with which his instrument is provided and removes his receiver. As a result 90 of this operation an idle finder switch at the exchange is set in motion and connects the subscriber's line in question with a trunk line extending to an operator's position. The operator is provided with means for 95 restoring a station thus trunked to her position to normal condition for calling, and in ordinary cases will do so, being free to use her judgment, however, and require the deposit of a coin, as is the practice in ordinary manual systems. The system may also be operated as a system requiring the sub-

scriber to pay before completing a connection by permitting the first call from a substation to be completed free, or by the equipment being rendered inoperative upon installation so that a coin must be deposited before a connection can be established.

The foregoing brief description will give a general idea of the scope of the invention. Further features and details of operation will be described hereinafter, reference being had to the accompanying drawings, in which there is shown diagrammatically the essential parts of an automatic telephone system embodying the invention.

Referring to the drawings, which should be placed in order with corresponding lines at the ends thereof in alignment, Fig. #1 shows at the left a substation A which includes talking equipment, a calling device S for controlling the automatic switches at the exchange, and coin collecting apparatus, together with relays and circuits for effecting the cooperation of the different elements. At the right of Fig. 1 there is shown an individual rotary line switch or trunk selector C, which is located at the exchange and whose function it is to connect the line of substation A, when calling, with a trunk line extending to an idle selector switch.

One of the trunk lines to which the line switch C has access is shown extending to the selector switch H (Fig. 2), which is one of a group of similar switches adapted to extend calling lines to idle trunk lines leading to desired groups of connector switches. One of these latter trunk lines is shown terminating in the connector switch I, shown only in part, which is adapted to complete connections to any one of a group of subscribers' lines, one of which is the line extending to substation A'.

The trunk line which terminates in the selector H has a branch shown at the left of Fig. 2 which is multiplied in the banks of a group of finder switches. One of these finder switches is indicated by the reference character F, and as shown is adapted to extend the afore mentioned branch to the operator's equipment O. This latter comprises a reversing key K', a pair of relays which will be described along with the rest of the equipment, and a key K² which is the well known listening key, by which the operator connects her head set (not shown) for conversation.

The substation telephone equipment and calling device, and the line, finder, selector, and connector switches referred to herein are in general well known in the art, and in order to obviate the necessity of a lengthy description reference is made to the following patents:

British patent to Dicker, #29,654 of 1910.

U. S. patent to Lamb, #1,193,160, granted 65 Aug. 1, 1916.

U. S. patent to Powell, #1,308,553, granted July 1, 1919.

U. S. patent to Keith, Erickson, and Erickson, #815,321, granted March 13, 70 1906.

U. S. patent to Keith, Erickson and Erickson, #815,176, granted March 13, 1906.

U. S. patent to Newforth, Reissue 75 #13,901, reissued April 13, 1915.

The operation of the system is as follows:

Assuming that the subscriber at substation A desires to secure connection with the subscriber at substation A', he will first 80 remove the receiver R (Fig. 1) from the hook after which he will operate his calling device S in accordance with the digits in the number assigned to substation A'. Upon the removal of the receiver, a circuit is 85 completed for the line relay 30 of the rotary line switch C as follows: ground at G², resting contact of armature 36 and the said armature, line conductor 26, normally closed contacts of push button P at the substation, 90 armature 10 and its resting contact, impulse springs 5 and 4 of the calling device S, winding of the polarized relay 6, transmitter T, receiver R, the working contact of the hook switch 1, line conductor 25, 95 armature 37 and its resting contact, and the winding of the line relay 30 to battery. The line relay is operated by closure of the above circuit and upon attracting its armature 34 completes a circuit for the switching relay 31 as follows: ground at G', 100 armature 34 and its working contact, winding of relay 31, interrupter contact of the motor magnet 32, and the winding of the said motor magnet to battery. At the same 105 time that this circuit is closed the private or test wiper 39 is connected to the circuit at a point midway between the relay 31 and the magnet 32 over the following path; test wiper 39, armature 35 and its resting 110 contact, armature 33 and its working contact, and thence to junction point 50. The operation now depends upon whether the trunk line with which the wipers of line switch C are associated is or is not busy, in 115 which former case the test contact 42 will have a ground potential upon it. Under these circumstances relay 31 will be short-circuited in an obvious manner and will not energize. At the same time the rotary magnet, being supplied with direct ground via the test wiper 39 and the busy test contact, 120 will operate to advance the switch wipers to the next set of contacts; and since the magnet interrupts its own circuit, this 125 movement will continue until the test wiper 39 engages an idle and ungrounded test contact, when the motor magnet will cease

operating. It should be mentioned here that relay 31 is of such high resistance that the motor magnet will not energize in series with it. Relay 31, being no longer short-circuited will then energize at once. In the present case we may assume that the trunk line shown is idle and that the test contact 42 therefore is ungrounded. This being the case, upon the energization of line relay 30, no operation of the motor magnet will take place, and relay 31 will energize immediately. By the attraction of armature 35 the test wiper 39 is connected to ground G^1 , whereby the trunk is instantly made busy to other line switches; and by the attraction of armatures 37 and 36, line conductors 25 and 26 are disconnected from the line relay 30 and ground, respectively, and are extended by way of wipers 38 and 40, bank contacts 41 and 43, conductors 44 and 46, armatures 112 and 108 of relay 100 and their resting contacts, armatures 113 and 115 and their resting contacts, the upper and lower windings of line relay 102 of selector H, and the upper and lower windings of relay 103 to battery and ground G^3 , respectively.

The calling line having been extended by the line switch C as described above, relays 102 and 103 of the selector H will energize in series over the calling subscriber's loop. Relay 103, upon attracting its armature 118 opens the starting circuit of the finder switch F and associated finder switches to prevent the starting of an idle finder switch at this time; while the line relay 102 at its armature 117 closes an energizing circuit for the slow acting relay 104. Relay 104, upon energizing, opens the circuit of the release magnet 127 at the resting contact of armature 121; prepares a circuit for the vertical magnet 128 at the working contact of the same armature; opens the finder switch starting circuit previously mentioned at another point at the resting contact of armature 120; and closes a holding circuit extending back to the line switch C which may be traced as follows: ground at G^4 , working contact of armature 119 and the said armature, conductor 170, contact spring 110, contact spring 111, conductor 45, bank contact 42, test wiper 39, armature 35 and its working contact, winding of relay 31 of the line switch C, and the winding of the motor magnet 32 to battery. A branch of the above circuit extends by way of private normal conductor 28 to multiple test contacts in the banks of connector switches which have access to the line of substation A, whereby the said line is made busy to incoming calls. It is understood that the holding circuit just described is established before the slow acting line relay 30 of line switch C has had time to deenergize.

65 The calling subscriber will now operate

his calling device in accordance with the first digit in the number of substation A', thereby producing in the well known manner a series of interruptions in the line circuit, resulting in a corresponding series of deenergizations of the relays 102 and 103 of the selector H. During the operation of the calling device the shunt springs 2 and 3 are closed in the well known manner to bridge the calling device directly across the line and excluding the polarized relay 6 and the talking instrumentalities R and T from the circuit. The deenergizations of relay 103 caused by the interruptions of the line circuit are of no effect at this time, for the finder switch starting circuit is held open by the slow acting relay 104 which retains its armatures attracted while impulses are being received. Relay 102, however, at each deenergization sends an impulse to the vertical magnet 128 over the following path: ground at G^4 , armature 117 and its resting contact, resting contact of armature 116 and the said armature, armature 121 and its working contact, low resistance winding of slow acting relay 105, and the winding of the vertical magnet 128 to battery. In response to these impulses the vertical magnet 128 operates to raise the selector shaft step by step until it arrives at the bank level in which terminate the group of trunk lines which extend to the desired group of connector switches. The slow acting relay 105 is energized in series with the vertical magnet and retains its armature attracted while the latter is being operated. At the first upward movement of the switch shaft the offnormal spring 125 closes its contact, whereupon a circuit is completed for the line switching relay 101 which may be traced as follows: ground at G^4 , working contact of armature 119 and the said armature, conductor 170, winding of the relay 101, armature 124 and its resting contact, offnormal spring 125 and its working contact, and the winding of relay 106 to battery. Relay 101 is not energized over the above circuit, however, for since relay 105 is in operated position at this time, ground G^4 is connected direct by way of armature 122 and its working contact to the offnormal spring 125, whereby it will be clear that relay 101 is short-circuited. Relay 106 energizing at once upon the closure of the offnormal contacts, locks itself to the ground at its armature 173, and at its armature 123 prepares a circuit for the rotary magnet 107. At the end of the series of impulses relay 105 deenergizes and closes a circuit which extends from ground G^4 by way of the working contact of armature 119 and the said armature, armature 122 and its resting contact, armature 123 and its working contact, and the winding of the rotary magnet 107 to battery. The rotary magnet 107 is thereupon energized to rotate

the selector wipers 130, 131 and 132 into engagement with the first set of bank contacts in the level, and interrupting at the same time the locking circuit of relay 106, which includes a section of the previously described circuit connecting relays 101 and 106 in series. Relay 106, upon deenergizing, opens the circuit of the rotary magnet 107, which upon deenergizing in turn, again completes the circuit including relays 101 and 106. The operation now depends upon whether the test contact with which the test wiper 131 is in engagement is busy or is not busy. If this test contact is busy it will be grounded, relay 101 will be short-circuited as before and relay 106 will again be energized, resulting in another closure of the circuit of the rotary magnet 107 and the consequent advance of the selector wipers another step. The rotary magnet thereupon interrupts the circuit of relay 106 as before, from which it will be seen that the rotation will continue as long as the test wiper continues to engage busy test contacts, the relay 106 operating as a stepping relay in conjunction with the rotary magnet 107. When the test wiper 131 arrives at a nonbusy or ungrounded test contact, which we will assume is the test contact 151, and the rotary magnet 107 deenergizes, relay 106 will not again energize, owing to the high resistance of the switching relay 101; and this latter relay, being no longer short-circuited, will energize. Upon energizing, relay 101 opens the release magnet circuit at its armature 116; shifts the connection of the test wiper 131 from its own upper terminal to its lower terminal at armature 114; and at armatures 113 and 115 disconnects the incoming line conductors from the windings of the line relay 102 and extends them by way of wipers 130 and 132, bank contacts 150 and 152, the normally closed sets of contact springs of the reversing relay 153 of the connector I to the upper and lower windings, respectively, of the line relay 154.

Upon the extension of the line circuit as above described, relay 154 is energized over the calling subscriber's loop, and upon attracting its armature, completes a circuit for the slow acting relay 155. Relay 155, upon energizing, closes a holding circuit for the selector H and the line switch C as follows: ground at G^o, conductor 171, test contact 151, test wiper 131, and armature 114 and its working contact to the junction point 172, where the circuit divides; one branch extending by way of winding of relay 101 and the winding of relay 106 to battery, and the other branch extending by way of contact springs 110 and 111 and the path previously traced through the switching relay 31 and the motor magnet 32 of line switch C to battery.

65 The calling subscriber will now operate

his calling device in accordance with the two final digits in the called number. As a result two more series of interruptions are produced in the line circuit, causing two corresponding series of deenergizations of the line relay 154. The line relay 154 operates to control the connector switch I through the medium of its vertical and rotary magnets to establish connection with the line of substation A'. Since the operation of the connector I is well known and is sufficiently described in the patents previously referred to, the operation will not be described in detail. It will suffice to say that upon the completion of the connection the bell at substation A' is automatically operated to signal the called subscriber, who upon lifting his receiver from the hook, connects his substation talking equipment across the line and thereby closes an energizing circuit for the back bridge relay 153 at the connector. Relay 153 has the usual function of a back bridge relay in a connector switch of this general character, that of reversing the incoming line conductors as regards their connections to the windings of the line relay 154, thereby reversing the direction of current flow in the calling line. As a result, the polarized relay 6 at substation A, which hitherto has remained inoperative, is now energized in the proper direction to enable it to operate its armature 9 which is locked by engagement with armature 10, and which when fully operated prepares a circuit for the high resistance relay 7.

The connection between the calling and called subscribers has now been established and they may converse as desired. The talking circuit through the automatic equipment is shown in heavy lines and will be readily understood. It will be noted that the path for voice currents includes the condenser at the substation, which is connected in parallel with the winding of the polarized relay 6.

When the subscribers are through talking they will both hang up their receivers. When the receiver is hung up at substation A the line circuit extending through the line switch C and selector switch H to the line relay 154 of the connector is interrupted and the said relay is permanently deenergized, resulting in the deenergization of the slow acting relay 155. Relay 155, upon retracting its armatures, causes the restoration of the connector I to normal position in the well known manner and at the same time removes ground from the holding circuit extending back to the selector H and the line switch C. At the selector switch the line switching relay 101 is now deenergized to close a circuit for the release magnet 127 which operates to restore the selector switch to normal position, its own circuit being interrupted at offnormal spring 126 when the shaft returns to

normal. At the line switch C relay 31 deenergizes to disconnect the line of substation A from the trunk line. At substation A, when the receiver hook reaches its lowest 5 position it comes into engagement with its resting contact and connects the high resistance relay 7 in bridge of the line as follows: line conductor 25, switch hook 1 and its resting contact, armature 9 and its 10 working contact, winding of high resistance relay 7, and the normally closed contacts of the push button P to the line conductor 26. Relay 7 is energized at once but is of such high resistance that it does not interfere 15 with the deenergization of the line relay 154 of the connector I and the subsequent release of the automatic switches. Upon energizing, relay 7 attracts its armature 10, which is held in operated position 20 by the engagement of the pin 14 with the tooth 15 of the escapement carried on the arm 12 of armature 11. The attraction of armature 10 causes the unlocking or release of armature 9, but it should be explained 25 that these armatures are so adjusted that armature 9 is not released until the pin 14 of armature 10 has passed the point of tooth 15 of the escapement, thus insuring that armature 9 will not be unlocked unless 30 by the same operation armature 10 is retained by the escapement. As a further result of the operation of armature 10, the lower line conductor 26 is disconnected from the branch path to the transmitter T which 35 extends through the calling device springs 5 and 4 and the polarized relay 6 and is connected instead to another branch excluding the said calling device which passes through the windings of the polarized relay 40 8.

The apparatus is now in condition characterized by the establishment of a successful connection and the subsequent release of the switching mechanism upon the completion 45 of conversation. Since the connection was successfully accomplished the subscriber at substation A will now proceed to pay for it by depositing a suitable coin, 5 cents for example, in the coin slot 16. As 50 the coin passes down the coin chute it engages the end of the arm 12 which projects into the coin chute and thereby actuates the escapement to release the pin 14 on armature 10, permitting the said armature 55 to return to normal position. It will be seen now that the substation A is in its original condition and is ready to establish another connection.

The foregoing describes the ordinary operation 60 of the system. Let it be assumed now, that by some mischance, when the line of substation A' was called, connection was accidentally established with some other line. The operation will be the same as has 65 been described except that upon the com-

pletion of the talking connection the calling subscriber will learn at once that he has the wrong number, whereupon he will so inform the answering subscriber and will hang up his receiver to release the connection. When the receiver is replaced, substation A is rendered inoperative for automatic calling by the switching of the circuit at armature 10 of relay 7, as has been 70 just described, and it will be apparent that ordinarily the subscriber would be forced to deposit another coin before he could proceed further. However, means are provided for remedying this evil and its operation 75 will now be explained.

When the subscriber finds himself in a predicament of this kind, he will press the push button P, and while holding it depressed, will again raise the receiver from the hook, after which the push button may 80 be released. The resistance r at substation A may be of about 1000 ohms and its inclusion in the line circuit by the reason of the separation of the push button springs when the receiver is removed has no effect on the line 85 switch C, which operates as usual to extend the line of substation A into connection with an idle trunk line, assumed, as before, to be the trunk line extending to the selector H. When the line circuit is extended to the line 90 relays 102 and 103 of selector H the former relay energizes, but relay 103, which is of relatively low resistance and is marginally adjusted, does not energize, with the result 95 that before the slow acting relay 104 attracts its armature 120 a circuit is closed over the starting wire 133 for a brief interval as follows: ground at G⁴, armature 117 and its working contact, armature 118 and its resting contact, armature 120 and its resting 100 contact, conductor 133, and the lower winding of relay 138 to battery. Relay 138 is energized and completes a locking circuit for itself as follows: ground at G⁴, working 105 contact of armature 119 and the said armature, conductor 170, conductor 134, upper winding of relay 138, and armature 140 and its working contact to battery. As a further result of the energization of relay 138, ground G⁵ is disconnected from the test contact 144 and its multiples in the banks of the group of finder switches of which finder switch F is one, and a circuit for starting 110 the operation of one of these finders is completed over the following path, it being assumed that the finder switch F is idle at this time: ground at G⁵, armature 139 and its working contact, common starting wire 146, armature 210 and its resting contact, and the winding of the line relay 211 to battery. Upon the closure of the above circuit, line relay 211 is energized, and at its armature 215 completes an energizing circuit for 115 slow acting relay 213; and also at the same armature completes a circuit which may be 120 125 130

traced through the windings of high resistance switching relay 205 and the motor magnet 212 in series to battery. Simultaneous with the closure of this latter circuit the 5 test wiper 203 is connected by the operation of armature 214 to a point midway between the winding of relay 205 and the motor magnet 212. The operation now depends on whether the test contact with which the 10 test wiper 203 is in engagement is grounded or is not grounded. If the trunk line associated with this test contact is busy the test contact will have ground potential on it, relay 205 will be short-circuited, and the 15 motor magnet, which is arranged to interrupt its own circuit, will operate as a buzzer to advance the finder switch wipers 201-204 inclusive, in search of the calling line.

But in the present case we may assume 20 that the wipers of finder switch F were standing on the set of contacts in which terminates the branch of the trunk line in use when the operation of the said finder was initiated, as shown in the drawing. Under 25 these circumstances, since ground has been disconnected from test contact 144, the switching relay 205 will energize immediately following the energization of the line relay 211. The motor magnet 212, as is well 30 understood, does not operate because of the high resistance of relay 205. Upon the operation of relay 205 numerous circuit changes are brought about: At armature 210 the starting wire 146 is shifted from the line 35 relay 211 to the armature 216 of the slow acting relay 213, whence it is connected to the starting wire 217 extending to the next finder switch when this latter relay deenergizes; at armature 208 the test wiper 203 is 40 disconnected; while at armatures 206 and 207 the line wipers 201 and 202 are connected to the trunk conductors 230 and 231 which extend to the equipment O at an operator's 45 position. As a further result of the energization of switching relay 205, a circuit is completed at armature 209 for the relay 100 in the trunk over the following path: ground at G⁶, armature 215 and its left hand working contact, working contact of armature 209 and the said armature, wiper 204, bank contact 145, conductor 135, and the winding of relay 100 to battery. Upon energizing, relay 100 at its armature 109 substitutes the grounded conductor 135 for the 50 grounded conductor 170 in the holding circuit extending back to the line switch C; and at its armatures 112 and 108 disconnects the incoming trunk conductors 44 and 46 from the windings of the line relay 102 of selector 55 C and connects them instead to the branch trunk conductors 137 and 136, respectively, whence they may now be traced via the bank contacts 142 and 143, line wipers 201 and 202, armatures 206 and 207 of the relay 205 (now energized), conductors 230 and 231,

and normally closed contact springs of the key K' to the upper and lower windings, respectively, of the double wound relay 220 at the operator's position. Relay 220 is thereupon energized and at its armature 222 completes an energizing circuit for the slow acting relay 221. This latter relay, upon attracting its armature 223, connects ground G⁷ to the holding circuit via conductor 232, whereby relays 205, 100, and 31 are maintained energized after the slow acting relay 211 has retracted its armature 215. 70

Returning now to the selector H, when the trunk conductors 44 and 46 are disconnected from the line relay 102 by the energization of relay 100, the line relay deenergizes and opens the circuit of slow acting relay 104, which upon deenergizing an instant later, closes the circuit of the release magnet 127 to restore the selector to normal; and at the same time removes ground G⁴ from conductor 170, thus breaking the locking circuit of relay 138. This relay accordingly deenergizes, removes ground from the starting wire 146, and connects ground to the test contact 144 again. It is noted that relay 138 deenergizes to ground test contact 203 before the slow acting relay 213 of the finder switch can retract its armature 216, thus insuring that the trunk line will be made busy before another finder switch can be started. 85

The foregoing operations have all occurred responsive to the actuation of the push button P at the substation A coincident with the removal of the receiver, and have resulted in the extension of the line circuit through the medium of the line switch C and the finder switch F to an operator's position, certain of the equipment thereat being represented by the reference character O, as previously mentioned. To proceed with the explanation, when the line relay 211 of the finder switch F was energized to start the finder switch, ground G⁶ was connected by way of conductor 232 and normally closed springs of the listening key K² to the lamp L, which is thus lighted to notify the operator that a call has been received. As soon as she perceives the signal, the operator will actuate her listening key K², thereby opening the lamp circuit and connecting her head set across the line for conversation. 105

At substation A, when the subscriber hears the operator on the line, he will tell her the facts in regard to his unsuccessful attempt to obtain a connection by the use of his dial, and an experienced operator will usually be able to tell at once whether the subscriber is entitled to a rebate or not. Failures due to calling wrong directory numbers, and those which appear to be due to some defect in the central office switches, will obviously be sufficient ground for a re- 115 120 125 130

bate without question on the part of the operator. Other cases will arise which are doubtful and if she desires the operator can check up on the calling subscriber's number 5 and then after remitting the charge, can enlist the aid of a service observer who will be able to detect habitual attempts to defraud the company. Since this, however, is more of a traffic detail with which we are not particularly concerned, the explanation will be proceeded with. In the present case, the subscriber being properly entitled to a rebate, the operator will actuate the key K' momentarily, whereby the conductors 230 and 231 are reversed as regards their connections to the windings of the double wound relay 220. As a result the direction of current flow in the line circuit is reversed and the polarized relay 8 at substation A is energized in the proper direction to enable it to operate its armature 11. The function of the escapement is to prevent the release of armature 10 before the reversing key is restored to normal by the operator as 25 otherwise the polarized relay 6 would be operated also. When the current is reversed and relay 8 responds to actuate its armature, the pin 14 is held by the tooth 13 of the escapement, which is understood to be set somewhat to the rear of tooth 15, until the current again changes its direction upon the release of the reversing key and armature 11 is restored. It will be seen now that the polarized relay 8 performs the same 30 function as does the deposit of a coin, that is, the restoration of substation A to normal condition for automatic calling.

The calling subscriber will now hang up his receiver to disconnect from the operator. 40 When the line circuit is opened, relays 220 and 221 at the operator's position will de-energize. By the deenergization of the latter relay, ground G' is disconnected from the holding circuit, whereupon relays 205, 100, and 31 will simultaneously deenergize and the switching apparatus will be ready for another call.

While not strictly necessary, it is deemed advisable to provide a signal preferably in the form of a semaphore or target controlled by the armature 10 as shown, in order to advise the subscriber at all times whether his telephone is in condition for automatic calling or not.

While I have described my invention in connection with a specific type of substation equipment or paystation, and utilizing certain specific types of automatic switches at the central office; I recognize that other types of switches may be used, and that the invention in its broader aspects is applicable to systems employing other types of measured service equipment, or even to systems which are not measured service, but 60 wherein it is desired that the subscribers be

given ready access to operators without having to manipulate their dials. I do not wish to be limited, therefore, to the precise circuits and apparatus shown herein, but desire to include and have protected by Letters Patent all forms of my invention which come within the scope of the appended claims. 70

What I claim is:

1. In a telephone system, a subscriber's line, a trunk line having two branches, an automatic switch for extending one of said branches to an operator's position, a second automatic switch for extending the other of said branches toward another subscriber's line, means for connecting said first line when calling with said trunk line, separate controlling devices for said switches, respectively, at the substation on the calling line, and a measured service device cooperating with one of said controlling devices to count the connections established via said second switch. 75 80 85

2. In a telephone system, subscribers' lines, an operator's position and a group of trunk lines at the exchange for connecting said lines therewith, a second group of trunk lines for use in interconnecting said subscribers' lines, a station on one of said lines comprising separate calling devices for controlling connections over the two groups of trunk lines, respectively, and measured service mechanism cooperating with one of said calling devices for requiring the subscriber to pay for connections with other 95 100 subscribers' lines. 90

3. In a telephone system, subscribers' lines, an operator's position, subscriber controlled automatic switching mechanism at the exchange whereby a calling subscriber 105 can extend his line to said operator or to another subscriber's line, a measured service device at the station on each of said lines for charging the subscriber with outgoing calls to other subscribers' lines, and operator 110 controlled mechanism at each station for remitting the charge on any call. 110

4. In a telephone system, a calling and a called line, automatic switches at the central office controllable by the subscriber on the calling line for connecting said lines, measured service mechanism at the station on the calling line for requiring the subscriber to pay for each connection, an operator's position accessible to the calling line, and mechanism under control of the operator for remitting the charge on unsuccessful connections. 115 120

5. The combination, in an automatic telephone system comprising subscribers' lines and automatic switches controllable thereover to connect said lines in conversation, of measured service mechanism at the station on one of said lines, whereby the subscriber thereat is charged for each connection, in- 125 130

dependent switching mechanism controlled by said subscriber for extending connection to an operator in case any connection is unsuccessful, and means controlled by the operator for remitting the charge.

6. In a telephone system, a plurality of subscribers' lines and automatic switches controllable thereover to connect said lines in conversation, measured service mechanism at the station on one of said lines controlling outgoing calls and requiring the subscriber to pay for each connection before he can obtain a second connection, independent calling means at said station not controlled by said mechanism, and other switches at the exchange responsive to said independent calling means for extending connections to an operator.

7. In a telephone system, a calling subscriber's line, a trunk line extending to an operator's position, a second line, automatic switches controlled by the subscriber on the calling line for completing connections with said second line, charging means requiring the calling subscriber to pay for all connections so extended, other switches operable by the calling subscriber independent of said charging means for connecting his line with said trunk line, and charge rebating means for rebating the charge on any connection.

8. In a telephone system, comprising subscribers' lines and automatic switching mechanism at the exchange for connecting calling and called lines in conversation, measured service equipment at the station on each line for assessing a charge against the subscriber thereat for each outgoing call, an operator's position, means controlled by a calling subscriber for extending a connection to the operator's position without charge, and operator controlled means for rebating the charge against such subscriber on a previous unsuccessful call.

9. In a telephone system, a calling subscriber's line, an operator's position and other subscriber's lines, automatic switches separately operable at the option of the calling subscriber for connecting his line with the operator's position or with one of said other lines, means requiring the subscriber to pay for calls to said other lines, and operator controlled means for rebating the charge in case the desired line is not obtained.

10. In a telephone system, a calling and a called line, automatic directly controlled switches for connecting said lines, automatic means for charging the calling subscriber for outgoing calls, an operator's position at the exchange, and operator controlled means for remitting the charge on unsuccessful calls.

11. In a telephone system, a calling subscriber's line, other subscribers' lines, auto-

matic switches at the exchange for connecting the calling line with a desired one of said other lines, a calling device at the station on the calling line for controlling said switches, mechanism at the calling station for rendering said calling device inoperative after every call, effective to charge the subscriber with a call and manually operable to restore said calling device to operative condition, another calling device at the calling station independent of said mechanism, an automatic trunking switch at the exchange responsive thereto to extend the calling line to an operator's position, and operator controlled means for restoring the said first calling device to operative position without charging the subscriber with a call.

12. In a telephone system, a calling subscriber's line, other lines, automatic switches at the exchange for connecting the calling line with a desired one of said other lines, a calling device at the station on the calling line for controlling said switches, mechanism at the calling station for rendering said calling device inoperative after every call, coin controlled means for restoring said calling device to operative condition, a circuit controller at the calling station independent of said mechanism, an automatic trunking switch at the exchange responsive thereto to extend the calling line to an operator's position, and means controlled by the operator for restoring said calling device to operative condition.

13. In an automatic telephone system, a substation including a calling device for controlling the switches at the exchange, means for rendering said calling device inoperative when the receiver is replaced after an outgoing call is completed, manually operable means effective to charge the subscriber with the call and at the same time restore said calling device to operative condition, and a relay adapted to be controlled by an operator for restoring said calling device to operative condition without payment by the subscriber.

14. The combination, in a telephone system, of a calling subscriber's station and line extending to a central exchange, a second line, automatic switches for connecting said lines, a normally operative calling device at the calling station for controlling said switches, and mechanism controlled by the replacement of the receiver at the calling station for rendering said calling device inoperative.

15. The combination, in a telephone system, of a calling subscriber's station and line extending to a central exchange, a second line, automatic switches for connecting said lines, a normally operative calling device at the calling station for controlling said switches, mechanism controlled by the

- replacement of the receiver at the calling station for rendering said calling device inoperative, and coin controlled mechanism for again restoring said calling device to operative condition. 5
16. The combination, in a telephone system, of a calling subscriber's station and line extending to a central exchange, a second line, automatic switches for connecting said lines, a normally operative calling device at the calling station for controlling said switches, mechanism responsive to the replacement of the receiver at the calling station for rendering said calling device inoperative, said mechanism being normally ineffectual, and means controlled by the response of the called subscriber for rendering said mechanism effectual. 10
17. The combination, in a telephone system, of a calling subscriber's station and line extending to a central exchange, a second line, automatic switches for connecting said lines, a normally operative calling device at the calling station for controlling said switches, mechanism responsive to the replacement of the receiver at the calling station for rendering said calling device inoperative, said mechanism being normally ineffectual, means controlled by the response of the called subscriber for rendering said mechanism effectual, and coin controlled mechanism for again restoring said calling device to operative condition. 15
18. The combination, in a telephone system, of a calling subscriber's station and line extending to a central exchange, a second line, automatic switches for connecting said lines, a normally operative calling device at the calling station for controlling said switches, mechanism controlled by the replacement of the receiver at the calling station for rendering said calling device inoperative, coin controlled mechanism for again restoring said calling device to operative condition, an operator's position accessible to the calling line while said calling device is inoperative, and operator controlled means for restoring said calling device to operative condition without payment by the subscriber. 20
19. The combination, in a telephone system, of a calling subscriber's station and line extending to a central exchange, a second line, automatic switches for connecting said lines, a normally operative calling device at the calling station for controlling said switches, mechanism responsive to the replacement of the receiver at the calling station for rendering said calling device inoperative, said mechanism being normally ineffectual, means controlled by the response of the called subscriber for rendering said mechanism effectual, coin controlled mechanism for again restoring said calling device to operative condition, an operator's position accessible to the calling line while said calling device is inoperative, and operator controlled means for restoring said calling device to operative condition without payment by the subscriber. 25
20. In a telephone paystation, a plurality of controlling relays, two parallel branch circuits each including one of said relays, a battery feed circuit for the transmitter including one or the other of said branches, and a switching device for substituting one branch for the other in said circuit. 70
21. In an automatic telephone paystation, a plurality of controlling relays, a calling device for controlling the automatic switches at the exchange, two parallel branch circuits, one including one of said relays and the other including another of said relays and the said calling device in series, a battery feed circuit for the transmitter including one or the other of said branches, and a switching device for substituting one branch for the other in said circuit. 75
22. In a telephone paystation, a plurality of controlling relays, two parallel branch circuits each including one of said relays, a battery feed circuit for the transmitter including one or the other of said branches, a switching device for substituting one branch for the other in said circuit, and a condenser permanently connected in the talking circuit so as to be in shunt of whichever one of said branches is included therein. 80
23. In an automatic telephone paystation, a plurality of controlling relays, a calling device for controlling the automatic switches at the exchange, two parallel branch circuits, one including one of said relays and the other including another of said relays and the said calling device in series, a battery feed circuit for the transmitter including one or the other of said branches, a switching device for substituting one branch for the other in said circuit, and a condenser permanently connected in the talking circuit so as to be in shunt of whichever one of said branches is included therein. 85
24. In a telephone system, a substation including a calling device, automatic switches at the exchange controlled by said calling device for establishing telephone connections, measured service apparatus for charging the subscriber with connections so established, another calling device at said substation, and automatic switches at the exchange responsive only to said second calling device. 90
25. In a telephone system, a calling subscriber's line, a second line, subscriber controlled automatic switches at the exchange for connecting said calling line with said second line, a normally operative calling device at the station on the calling line for 125
- 60
- 65

controlling said switches, means for rendering said calling device inoperative after every successful call, subscriber controlled charging means adapted when actuated to render said calling device operative, and a signal for indicating to the subscriber whether his calling device is operative or inoperative.

26. In a telephone system, a subscriber's station and line extending to a central exchange, an automatic switch at the exchange for use in extending said line, a controlling device at the station for said switch, and circuit connections whereby the said switch is prevented from responding unless the subscriber takes off his receiver while said controlling device is being actuated.

27. In a telephone system, a substation and line extending to a central exchange, independently operable circuit controlling devices at said station connected in series with each other and the two conductors of said line, an automatic switch at the exchange responsive to a first one of said devices while the second device is in normal position, and a second automatic switch controlled by cooperation of both said devices and responsive to the first device when and only when the second device is maintained in operated position.

28. In a telephone system, a subscriber's line, a trunk line at the exchange comprising two normally connected sections, the second of which terminates in an automatic switch, a branch of said trunk line extending from the junction of said sections to a second switch, subscriber controlled means for extending a connection over said trunk via said first switch while maintaining said second switch in normal position, and subscriber controlled means for disconnecting said sections and for connecting the first section to said branch for extending a connection via said second switch.

29. In a telephone system, a line, a branched trunk line at the exchange having a normally connected and a normally disconnected branch at the divided end thereof, each branch terminating in an automatic switch, means for connecting said line with the undivided end of said trunk line, a calling device at the station on said line for controlling the switch associated with the said normally connected branch, and a second calling device at said station effective when operated to actuate the switch associated with the said normally disconnected branch and to connect said branch to the trunk line in place of the other.

30. In a telephone system, a line, a trunk line at the exchange having two branches at one end, one branch terminating in an automatic selector switch and the other in the bank of a finder switch, means for connecting said line with said trunk line at the

undivided end thereof, independent controlling devices at the station on said line for operating said switches separately, and a switching device for disconnecting the branch terminating in said selector switch and for connecting the branch terminating in said finder switch whenever the latter is operated.

31. The combination, in an automatic telephone system comprising subscribers' lines and automatic directly controlled connecting switches at the exchange, of automatically operated means individual to each station for charging outgoing calls to the subscriber thereat, and operator controlled refunding means individual to each station for rebating the charge on unsuccessful calls.

32. The combination, in an automatic telephone paystation, of automatically operated charging means, whereby the subscriber is required to pay for successful calls, operator controlled refunding means for rebating the charge on unsuccessful calls, and automatic switches at the exchange directly controlled by the subscriber for setting up connections.

33. In a telephone system, subscribers' lines, measured service apparatus at the station on each line, automatic first selector switches at the exchange operable in establishing talking connections only under control of said apparatus and other automatic switches at the exchange operable independent of said apparatus.

34. In a telephone system, a subscriber's line extending to a central exchange, coin collecting mechanism at the station on said line, automatic first selector switches at the exchange controllable from said station in establishing talking connections only when coins are deposited in said mechanism, and other automatic switches at the exchange controllable from said station without depositing coins.

35. In a telephone system, automatic switches for connecting calling and called lines, measured service equipment for each line for charging for outgoing calls, means for releasing established connections, an operator's position, automatic switches for extending any calling line to said position after a previously established connection has been released, and operator controlled means for rebating the charge against such line if the previous connection was unsuccessful.

36. In a telephone system, automatic switches for connecting calling and called lines, measured service apparatus for each line controlled over called lines when connections are established for charging such connections to the calling lines, an operator's position, means whereby any calling subscriber can release an unsuccessful con-

nection and extend his line to said position, and operator controlled mechanism for rebating the charge.

37. In a telephone system, a calling and a called line, automatic switches for connecting said lines, paystation mechanism on the calling line controlled over the called line to require the calling subscriber to pay for the connection, an operator's position, means whereby the calling subscriber can release the connection and cause his line to be connected with said operator's position, and means whereby the operator can control said mechanism to rebate the charge on the previous connection.

38. In a telephone system, a calling and a called line, automatic switches for connecting said lines, a calling device at the calling station for controlling said switches, paystation mechanism controlling said calling device and requiring the calling subscriber to pay for the connection before another connection can be established, an operator's position, means whereby the calling subscriber can extend his line to said position after releasing the previous connection, and means whereby the operator can control said mechanism to permit the subscriber to establish the next connection free of charge.

39. In a telephone system, automatic switches controllable by a calling subscriber for extending a connection to a called line, paystation mechanism on the calling line for requiring the calling subscriber to pay for each connection so established, means whereby the calling subscriber can notify an operator at the exchange in case any connection is unsatisfactory, and means whereby the operator can then control the said mechanism so as to enable the subscriber to make the next call free of charge.

40. The combination, in a telephone paystation, of automatically operated charging means for assessing calls against the subscriber, means responsive to payment of assessed charges for restoring the charging means, and means for restoring the charging means without payment to rebate the charge on unsuccessful calls.

41. The combination, in an automatic telephone paystation, of automatically operated charging means adapted to discriminate between an answered and unanswered call and assess the former against the subscriber, whether the right party was secured or not, means responsive to payment of the assessed charge for preparing the charging means to handle the next call, and independent means operable without payment for preparing the charging means to handle the next call, whereby the charge may be remitted if the last call was unsuccessful.

42. In an automatic telephone system,

means comprising automatic directively controlled switches for connecting calling and called lines, means consisting solely of automatic non-directive switches for connecting calling lines with an operator's switchboard, and measured service equipment operating automatically to charge the calling subscribers for the calls to other lines but not for the calls to the operator's switchboard.

43. In a telephone paystation, charging means operable to require the subscriber to pay for a connection, a magnet controlled over the line from the exchange, means for receiving coins, and means responsive either to the energization of said magnet or to the deposit of a coin for restoring said charging means.

44. In a telephone paystation, two polar relays, the first of which is normally connected in the line circuit extending to the exchange, and a third relay energized over the line for substituting the second of said polar relays for the first.

45. The combination with a subscriber's station and a line extending to the exchange, of a calling device included serially in the line circuit for controlling the exchange switches, and a relay energized over the said line for disconnecting one side of the calling device from the line and for closing the line over a new path.

46. In a telephone paystation for use in automatic telephone systems, a calling device for controlling the automatic switches at the exchange, and a relay energized over the line from the exchange for opening the circuit of said calling device to render it ineffective.

47. In a telephone paystation, three magnets all adapted to be energized over the line from the exchange, locking means for the first magnet controlled by the second magnet, and locking means for the second magnet controlled by the third magnet.

48. In a telephone paystation, two relays and a magnet, all adapted to be energized over the line from the exchange, means for locking the first relay when energized, means for locking the second relay when energized and for unlocking the first relay, and means for unlocking the second relay when the magnet is energized.

49. In an automatic telephone system, a subscriber's station including a calling device for controlling the automatic switches at the exchange, measured service equipment capable of rendering said device inoperative in order to make the subscriber pay for his connections, and a visual indicator at said station for advising the subscriber whether the calling device is operative or not.

50. In a telephone system, a subscriber's station including two manually operable line circuit controlling devices, a line for

said station extending to the exchange, a backward selecting line finder switch for extending said line and starting means for said finder responsive only to the simultaneous operation of both said devices.

51. In a telephone exchange system, calling lines, paystations for said lines, called lines of two classes, means for extending

connections to lines of either class, and circuit arrangements at the exchange rendering it necessary to deposit coins only in case lines of a particular class are called.

Signed at Chicago, county of Cook and State of Illinois, this 13th day of Sept., 1919.

RODNEY G. RICHARDSON.
